UNITED STATES PATENT OFFICE

JAMES E. HARDING, OF LYME, CONNECTICUT

SYRINGE PLUG

Application filed April 15, 1929. Serial No. 355,389.

This invention relates generally to syringes and has particular relation to an article of manufacture capable of transforming the ordinary fountain pen into a syringe.

The main object of my invention is to provide a simple attachment for the known self-filling fountain pen and in the nature of an article of manufacture which is capable of converting the pen into a syringe. A further object is to provide an attachment for fountain pens which permits conversion of a fountain pen into a syringe whenever desired. A further object is to provide a simple and durable attachment for fountain pens.

Other objects will be in part obvious from the annexed drawing and in part indicated from the following analysis of the invention, in which reference is made to the accompanying drawing illustrating an embodiment of my idea.

In the drawing corresponding parts are indicated by similar reference characters.

Fig. 1 is a partial section of a conventional self-filling pen, the removed pen and feed plug being shown in dotted lines;

Fig. 2 is an elevation of the syringe plug in accordance with my invention;

Fig. 3 is a section thru a conventional self-filling fountain pen with the syringe plug associated therewith to convert the pen into a syringe;

Fig. 4 is an elevation of a modified form of syringe plug;

Fig. 5 is a section of the syringe plug illustrated in Fig. 4 associated with the pen barrel.

Referring now to the drawing and particularly to Figs. 1 to 3 thereof, the usual self-filling fountain pen comprises a main barrel 10, the forward end of which has an undercut portion 10^a cooperating with an annular shoulder 10^b of the pen head 11, the latter forming an extension of the said barrel member. The head 11 carries an inner barrel member 12 to which is secured a bladder 13 forming the ink reservoir. A feed plug 15 having a feed port 16 therein snugly fits within the member 12, and supplies ink to a pen 17.

In accordance with my invention, I provide a syringe plug, generally designated at 20, to be inserted into the tubular member 12 upon withdrawal of the feed plug 15 and pen nib 17. The said syringe plug comprises generally a cylindrical body portion 21 of a diameter to make a tight fit in the tube 12, and is of a length to provide a sufficient gripping area or surface therewith. A shoulder 22 may be formed on the plug 20 which defines a portion of increased diameter designated at 23, although it will be understood that the said shoulder may be dispensed with or eliminated to facilitate manufacture and assembly, and the plug 20 formed of a uniform exterior diameter throughout. The forward end 24 which forms the nozzle of the syringe is generally tapered, the taper being either a section of a cone or a section of an oblate, or a prolate spheroid. The plug is centrally bored as indicated at 26, the bore passing longitudinally thru the plug and being a hole, sometimes as small as one-sixty-fourth of an inch in diameter, or as large as one-eighth of an inch in diameter to accommodate liquids of different viscosities.

Upon removal of the feed plug 15 and the pen 17, the plug 20 is inserted into the inner barrel 12 and is securely held therein by reason of its tight fit. The shoulder 22 of the plug, when provided, bears against the end of the tubular member 12 to form a sizable thrust area. It will be understood that the ink has been exhausted from the bladder 13 and replaced with an antiseptic or other desired fluid. This fluid is thereafter fed thru the bore 26 of the plug and delivered thru the nozzle portion 24 thereof in a way similar to the ordinary syringe. The antiseptic is drawn into the bladder or reservoir in the same manner that the pen is filled and may be forcefully expelled therefrom thru the syringe plug upon the extension of the feed lever or equivalent device (not shown), with which substantially all self-filling fountain pens are supplied.

In the modified form of syringe plug illustrated in Fig. 4, the plug is provided with the portions 30, 31 and 32 of stepped diam-

eters, of which I designate the portion 31 as the "body portion," with thrust shoulders 33 and 34 formed between said portions. The forward end 35 of the plug forms a nozzle as above described. A bladder 36 is cemented or otherwise secured to the portion 31 of the plug, the bladder extending to the shoulder 33.

When desirable to use this modified form 10 of syringe plug with a fountain pen, the head portion 11 is removed from the barrel 10, carrying with it the inner barrel 12 and bladder 13. The syringe plug is then forced into the barrel 10, the forward end 15 thereof engaging the shoulder 34 of the plug. It will be understood that the diameter of the body portion 31 is such as to fit snugly within the barrel. The plug carries the bladder or fountain thru its connection 20 with the portion 30 in a manner similar to the mounting of the bladder 13 on the tubular barrel 12 of Figs. 1 and 3. Although it is preferable to utilize the shoulder 34 of the syringe plug to limit the insertion of the 25 plug into the barrel 10, this shoulder may be eliminated to facilitate manufacture, thus making the maximum diameter of the plug that of the body portion 31 thereof. The nozzle portion 35 is tapered and is in section, 30 like that of the plug shown in Figs. 2 and 3, a section of a cone, an oblate, or a prolate spheroid.

The advantages of the plug construction shown in the above are believed to be obvious. Briefly, the plug may be carried as an adjunct to the usual self-filling fountain pen. By removal of such parts therefrom as above indicated, and upon insertion of the syringe plug, the pen may be quickly converted into a syringe and is capable of all the uses to which a syringe is adapted to be put. The syringe plug is inexpensive in manufacture and is sufficiently small to be carried in a pocket or with a medical kit 45 or the like.

It will be seen that the several objects of the invention are achieved and other advantageous results attained. As many changes could be made in carrying out the 50 above invention, without departing from the scope thereof, it is intended that all matter contained in the above description or shown in the accompanying drawing shall be interpreted as illustrative and not in a limiting sense.

I claim:

1. An attachment for converting a fountain pen into a syringe consisting of a substantially cylindrical plug having a body 60 portion of a diameter snugly fitting within the pen barrel upon removal therefrom of the pen nib and feed plug, and having a tapered nozzle portion extending therefrom, the plug being provided with a longitudinal bore delivering thru the nozzle portion.

2. An attachment for converting a fountain pen into a syringe consisting of a plug having a substantial cylindrical body portion adapted to fit snugly within the pen barrel upon removal therefrom of the pen nib and feed plug and a tapered nozzle portion extending therefrom, said portions having a shoulder formed therebetween, the plug being provided with a longitudinally extending bore delivering thru said nozzle. 70

3. An attachment for converting a fountain pen into a syringe, a plug having a substantially cylindrical body portion of a diameter to snugly fit within the pen barrel upon removal therefrom of the pen nib and feed plug and a portion of reduced diameter at one side thereof about which a bladder member of the pen is adapted to be secured, the plug having a tapered nozzle portion extending from the other side of the body 80 portion, the plug being provided with a longitudinal bore extending therethrough and delivering to said nozzle. 85

4. A syringe comprising, in combination, a barrel of a fountain pen, a plug having a cylindrical body portion of a diameter to fit snugly within the barrel and having a tapered nozzle extending beyond the barrel, the plug being provided with a longitudinally extending bore communicating with 90 the interior of the bladder and delivering to the nozzle. 95

5. A syringe comprising, in combination, a barrel of a fountain pen, a plug having a cylindrical body portion of a diameter to fit snugly within said barrel, the body portion terminating in a shoulder, the plug having a tapered nozzle beyond said shoulder adapted to extend beyond the barrel, the plug being provided with a central longitudinal bore communicating with the interior of the bladder and delivering to the nozzle. 100

6. A syringe comprising, in combination, a barrel of a fountain pen, a plug having a cylindrical body portion of a diameter to fit within the barrel, a cylindrical portion of reduced diameter at one end of the body portion, and a tapered nozzle portion at the other end thereof, and a bladder member 110 adapted to be secured about said portion of reduced diameter, the plug having a longitudinal bore communicating with the interior of the bladder member and delivering to the nozzle member. 115

Signed at Lyme, Connecticut, this 31st day of March, 1929.

JAMES E. HARDING.
